UNITED STATES PATENT OFFICE.

GEORGE T. F. CLARKE, OF SPRINGFIELD, MASSACHUSETTS, ASSIGNOR TO BROOKS BANK NOTE COMPANY, OF SPRINGFIELD, MASSACHUSETTS, A CORPORATION OF MASSACHUSETTS.

DISPLAY-STAND.

1,142,933.

Specification of Letters Patent. Patented June 15, 1915.

Application filed October 2, 1914. Serial No. 824,598.

To all whom it may concern:

Be it known that I, GEORGE T. F. CLARKE, a subject of the King of Great Britain, residing in the city of Springfield, county of Hampden, and State of Massachusetts, have invented certain new and useful Improvements in Display-Stands, of which the following is a specification.

This invention relates to pasteboard easels or display devices. It is more particularly concerned with such devices as are adapted to support and display for advertising purposes various articles in package form, such as candies, fancy cheeses and the like.

15 An object of the invention is to provide an improved display device, which is of simple construction, and, consequently, inexpensive to construct.

Another object is to provide an improved device of the class described, the parts of which are few in number and readily formed without the use of elaborate dies.

25 A further object is to provide an improved display device which is collapsible, when not in use, and which can be folded into a flat form convenient for shipping.

Other objects and advantages will appear in the detailed description and annexed claims to follow.

30 In general, my device is formed from two cardboard members. The first or face member comprises a vertically arranged cardboard with two or more rectangular openings therein. These openings are formed

35 by cutting along three sides of a rectangle which leaves a tab foldable on the lower edge of the opening. The second member comprises a foldable supporting piece which is secured to the face member. The second

40 member is foldable into vertically disposed channels which are arranged one at the rear of each opening in the face member. This supporting member is adapted to be folded flat against the face member, when the display device is not in use. It is also adapted

45 to be held in channel forming position by folding the rectangular tab portions, cut from the openings in the face member, along the lower uncut edges of the openings rearwardly into the channels. Thus each rectan-

50 gular portion forms a closure for the bottom of its channel and the surplus of the tab not used for the closure is folded upwardly against the rear wall of the channel. By this

55 arrangement convenient pockets are formed

for the reception and display of merchandise.

A preferred form of my invention is shown in the accompanying drawings in which:

Figure 1 is a perspective view looking at the front of my display device. Fig. 2 is a perspective view of the rear thereof and, Fig. 3 is a sectional elevation taken on the line 3—3 of Fig. 2.

Referring to the drawings: 1 represents the face member which is shown cut in rectangular form but which may be formed in any other desired shape. This face member 1 is adapted to contain the usual lithographed advertisements relating to the articles displayed. The member 1 is provided with a series of rectangular openings 2 which are formed by cutting rectangular portions in the face member, along the lines 12, 13 and 14. The lower edge 15 of each rectangular opening is, however, left uncut. Thus tabs equal in size to the openings 2 are formed which are foldable on the edges 15.

Secured to the rear of the face member 1 is a foldable supporting member 16. The latter is folded to form a vertically arranged channel 7' at the rear of each rectangular opening 2. Thus, in Fig. 2, 7 represents the rear walls of the channels 7'. The outer edge of each wall 7 is connected by integral forwardly bent portions 6 to extension portions 5 which lie parallel and are secured to the member 1. The inner or adjacent edge of each wall 7 is similarly connected by integral forwardly bent portions 8 to a common portion 9. The portions 5 and 9 are secured to the face member 1 by any suitable means such as adhesive.

The rectangular portions cut from the openings 2, are adapted to be folded rearwardly within the channels 7' formed by the supporting member 16, as shown in Fig. 3. These rectangular portions are folded along the uncut edges 15 rearwardly and perpendicularly against the rear walls 7. Thus a bottom 3 is formed for each channel. The remaining portions 4 of the rectangular portions not used for the bottom closure are folded along the lines 11 and brought upwardly against the rear walls 7, as clearly shown in Fig. 3. It is to be noted particularly that when the portions 3—4 have been folded into the channels formed by the rear supporting member, the latter is positively

held in channel forming position. Furthermore, a pocket, closed on all sides except the front and top, is provided wherein articles can be received and displayed. The articles displayed, when inserted within these pockets, are forced against portions 4. The pressure of the article which may be partly supported on edge 15 against the wall 7 and the portion 4 causes sufficient frictional engagement therebetween to prevent the bottom portions 3 from falling downwardly.

The supporting member 16 comprising the portions 5, 6, 7, 8, and 9 extends from the bottom of the face member 1 to a position slightly above the top of the rectangular openings 2, as clearly shown in Fig. 2. Thus this member forms a rearwardly extending base portion to support the device. An extension of the base to still further support the device and prevent tipping thereof is provided by the triangular tabs 10. The latter are cut from the outer side of each back wall 7 and are foldable into the same plane as the side walls 6.

Thus, I have provided an improved display device which is extremely simple and which can be formed without the use of elaborately shaped dies. This device, as has been described, is formed from two rectangular pieces of cardboard and the cutting operations on these two members are of the simplest sort. Moreover, the device is collapsible into a form for convenient shipment and is also quickly foldable into form for display purposes. No elaborate devices are necessary to hold the rear supporting member in channel forming position but rather extremely simple and novel devices, comprising the foldable tabs 3 and 4 are employed.

It is recognized that many modifications may be made in the structure herein disclosed without departing from the scope of my invention as defined in the appended claims.

What I claim is:

1. A display device comprising a vertically arranged member on which advertisements may appear, an opening formed

therein by cutting a rectangular portion of said face member on all but the lower edge thereof, a supporting member fastened to the rear of said face member folded to form a vertically disposed channel at the rear of said opening, said channel extending from the bottom of said face member to a position above said opening, means on said supporting member foldable rearwardly therefrom to further support said device, said supporting member adapted to be folded flat against said face member and also adapted to be held in channel forming position by folding said rectangular portions along the uncut edge thereof, rearwardly into said opening, whereby a bottom closure for said channel is formed, and thereafter folding said portion upwardly against the rear wall of said channel, said supporting member and rectangular portion adapted to form a pocket for the reception and display of merchandise.

2. A display device, comprising a vertically arranged face member, an opening formed therein by cutting a rectangular portion of said face member on all but the lower edge thereof, a supporting member fastened to the rear of said face member folded to form a vertically disposed channel of rectangular cross section at the rear of said opening, said channel extending from the bottom of said face member to a position above said opening, said supporting member arranged to be folded flat against said face member for shipping purposes and also arranged to be held in channel forming position by folding said rectangular portion along the uncut edge thereof rearwardly into said opening normal to the walls of said channel, whereby a bottom closure for the channel is formed, and thereafter folding said portion upwardly against the rear wall of said channel, said supporting member and rectangular portion adapted to form a pocket for the reception and display of merchandise.

GEORGE T. F. CLARKE.
